UNITED STATES PATENT OFFICE.

GUSTAVE J. MERSEBURGER, OF WOODSIDE, NEW YORK.

TWO-FACED DOLL.

Application filed March 1, 1926. Serial No. 91,403.

The main object of this invention is to provide a doll's head having a double face, one at the back of the article and one at the front, and a cap which serves as a hood and is adapted to cover one of the faces. This doll's head may be applied to the body of a doll or may be mounted upon a base or pedestal to serve as an advertising medium.

Another object is to provide a head having a double face, either one of which may be covered by a tiltable hood.

The above and other objects will become apparent in the description below, in which characters of reference refer to like-named parts in the drawing.

Referring briefly to the drawing, Figure 1 is a side elevational view of the article.

Figure 2 is a front elevational view of the same with parts in section.

Figure 3 is a sectional elevational view of the preferred type of hood used on the doll's head.

Figures 4 and 5 are different modifications of hoods.

Referring in detail to the drawing, the numeral 10 indicates the base of a doll's head, which when used with the body of a doll, may serve as the neck, or when the article is used as an advertising or display medium, may serve as the base upon which the article is mounted. A hollow member of material is mounted on the base 10 and is substantially spherical in form, having opposing somewhat flat sides upon one side of which the image of a normal face 11 may be cast and diametrically opposite, a weeping face 12 may be formed, as illustrated in Figure 1. Centrally between these faces, a pair of openings are formed in the wall 13 of the head, one on each side of the faces and thru these openings, which are mutually aligned, a spindle 14 is passed. The spindle serves as a supporting element for a hemi-spherical cap 15 which fits over and covers one entire face when the cap is angularly supported, as illustrated in Figure 1. The cap shoulders upon a fluted portion 16 of the base 10 and extends angularly upward, alternately covering or uncovering either one of the faces.

The cap is rigidly mounted on the ends of the spindle 14, which latter has nuts 17 secured thereon, said nuts being preferably covered by ribbon rosettes, as illustrated in Figure 1. The spindle passes diametrically across the bottom or open end of the hemi-spherical hood 15, and to said spindle, a vertically extending stem 19 is fixed. At the upper end of the stem 19, a weight 20 is provided. This weight is adapted to swing within the hollow chamber 21 of the doll's head and cause the hood when it has passed dead center, to swing to a position of rest and cover alternately either of the faces 11 or 12. In Figure 4, a modified type of hood is shown. This modified type of hood 22 is hemi-spherical in outline, open at the bottom, is provided with openings 23 thru which the spindle 14 is adapted to pass, and around its open edge, a weighted rim 24 is formed which tapers toward its smallest dimensions at a position where the openings 23 are formed. In Figure 5, still another form of hood is shown. This hood 25 is hemi-spherical and at its axis, a cup 26 projects inwardly. The cup-shaped portion is filled with lead or some other weight-giving material 27 for the purpose of serving as a means for tilting the hood to cause it to fall and conceal one of the faces when said hood is rotated past dead center.

The article may be used either as providing a head for a doll or as an advertising display element. These faces 11 and 12 are alternately concealed from view by the hood, which is applied to the same. When any of the hoods is rotated slightly past dead center, they fall in the same direction and rotate to the position shown in Figure 1, completely concealing one face and disclosing the opposite one. The weight member, such as that indicated by the numeral 27 may project partly into member 15 thru an opening and have an outside projecting head such as indicated in Figure 5.

It is to be noted that certain changes may be made in form and construction without departing from the spirit and scope of the invention.

I claim:—

In a device of the class described, a head having opposing faces, said head being hollow, a spindle mounted rotatably in said head, a hemi-spherical hood supported on said spindle, said spindle being rigid and rotatable with said hood, a stem extending

vertically from said spindle, and a weight mounted at the upper end of said stem for unbalancing the hood when the latter is tilted to off dead center upon the head.

In testimony whereof I affix my signature.

GUSTAVE J. MERSEBURGER.
